CLAIM

We claim the ornamental design for a suction control valve, as shown and described.

DESCRIPTION

FIG. 1 is a top perspective view of a suction control valve according to the new design;

FIG. 2 is a right side view of the suction control valve shown in FIG. 1;

FIG. 3 is a left side view of the suction control valve shown in FIG. 1;

FIG. 4 is a rear elevation view of the suction control valve shown in FIG. 1;

FIG. 5 is a front elevation view of the suction control valve shown in FIG. 1;

FIG. 6 is a top view of the suction control valve shown in FIG. 1; and,

FIG. 7 is a bottom view of the suction control valve shown in FIG. 1.

In the drawings, the broken lines form no part of the claimed design.

1 Claim, 6 Drawing Sheets
